CLAIM

We claim the ornamental design for a firearm stock, as shown and described.

DESCRIPTION

FIG. 1 is a perspective view of a firearm stock according to a first embodiment.

FIG. 2 is a right-side view of the firearm stock of FIG. 1.

FIG. 3 is a left-side view of the firearm stock of FIG. 1.

FIG. 4 is a front view of the firearm stock of FIG. 1.

FIG. 5 is a rear view of the firearm stock of FIG. 1.

FIG. 6 is a top view of the firearm stock of FIG. 1.

FIG. 7 is a bottom view of the firearm stock of FIG. 1.

FIG. 8 is a perspective view of a firearm stock according to a second embodiment.

FIG. 9 is a right-side view of the firearm stock of FIG. 8.

FIG. 10 is a left-side view of the firearm stock of FIG. 8.

FIG. 11 is a front view of the firearm stock of FIG. 8.

FIG. 12 is a rear view of the firearm stock of FIG. 8.

FIG. 13 is a top view of the firearm stock of FIG. 8; and,

FIG. 14 is a bottom view of the firearm stock of FIG. 8.

The portions of the firearm stock shown in broken lines are included for the purpose of illustrating environment and form no part of the claimed design.
